PROCESS FOR CONVERSION AND HYDRO-
GENATION OF HEAVY PETROLEUM OILS
AND APPARATUSRalph H. McKee, New York, N. Y., assignor to
U. S. Hydrogenation Corporation, a corpora-
tion of Nevada

Application September 23, 1932, Serial No. 634,501

11 Claims. (Cl. 196—53)

The object of the present invention is to provide a method for the continuous conversion or cracking and hydrogenation of heavy petroleum oils into hydrocarbon liquids of lower boiling points, and apparatus therefor.

5 In commercial processes of cracking heavy petroleums to produce motor fuels, it is customary to pass the petroleum through a heated zone, allowing the vapors to remain at high temperature for a period of time and then separating the resulting motor fuel from the heavy residual oils. This heavy stock carries carbon and is objectionable as cracking stock, for again passing through the cracking apparatus, in that it is not only more difficult to crack than the original oil, but has a greater tendency to deposit coke in the apparatus.

10 By the present invention, a cracking and/or conversion process is provided capable of operation in a single furnace for treatment of the original charged stock and the residual heavy oils in a second cycle, without the use of an additional cracking chamber and without the deposition of coke or carbon in the tubes or elsewhere except 15 in traces.

It has been proposed in the prior art, to crack under high hydrogen pressures and in the presence of catalysts, but the yield of motor fuel has been found to be relatively low, and the method 20 is an expensive one to operate due to the cost of the hydrogen of which a substantial proportion passes out with the hydrocarbon gases formed in the cracking process. The apparatus required is 25 exceedingly expensive and the pressures used are so high as to make the process a difficult one to operate.

It has also been proposed in the art to employ 30 water vapor and catalyzing mediums in cracking heavy liquid hydrocarbons with a view to securing hydrogenation of the oil materials.

A specific object of the present invention is to 35 simultaneously provide a process for cracking and hydrogenating heavy liquid hydrocarbons to produce hydrocarbons of lower boiling points such as motor fuel, and simultaneously, in the same apparatus, re-crack the heavy oils for the production of more motor fuel. The process is one which essentially changes all of the heavy liquid hydrocarbons such as a crude petroleum oil, fuel oil, gas oil, etc., into non-condensable gas and motor fuel, with the production of either no or insignificant amounts of carbon and heavy residual oils.

A further object is to obtain a high recovery of 40 low boiling-point hydrocarbons from crude pe-

troleum or other heavy liquid hydrocarbons by the simultaneous treatment of the latter, or of the residual oil (obtained from such heavy liquid petroleum by cracking), with steam and hydrogen preferably in the presence of a catalyst.

In this process, polymerization of the products during the cracking process is largely avoided, notwithstanding the fact that the hydrogen is used under a pressure which is atmospheric, or, at least, inconsiderable as compared with the pressures used in the so-called "Berginization" of oil.

The invention may be described best, by reference to the accompanying drawing, which is a diagrammatic elevation, being partly in section.

The kiln 1, which may be of any desired construction or size, contains three coils, the upper coil 2 being for the pre-heating of water. It may, if desired, be of the same type of construction as the lower coils. The middle coil 3 is for the simultaneous injection of the water which has been pre-heated in the upper coil and the oil which is to be cracked. In a single kiln there may be present a series of coils, the same being duplicates of coils 2, 3, and 6. Coils 3 and 6, 20 25 may, if desired, have their units set vertically instead of horizontally.

In operation of the process, pressure will be built up in air tank 14 by means of pump 15 and the air will be led through suitable pipes, 30 as shown, to the oil and water tanks 16 and 17 respectively, the latter having gauges 18. The water will be fed under pressure through pipe 19 to heating coil 2 and thence through pipe 18x and branch pipe 19x to a suitable injector communicating with the inlet end of the primary coil 3. The oil is fed under pressure through pipe 20 to branch pipe 21 to an injector within the inlet end of primary coil 3. The heat treated vapor comes in contact with a catalyst 5 within 40 the outlet end of coil 3. The vapors then pass through pipe 22 to a separating tank 11, the residual oil dropping to the bottom of the tank, the latter being inclined and draining into pipe 24 which communicates with the inlet of a secondary coil 6, the discharge end of which contains a catalyst 5x.

The outlet end of the secondary coil 6 communicates with a discharge pipe 25 which may lead to a condenser, as, for example, condenser 50 26, or, discharge pipe 25 may be closed by valve 27 and the vapors led through pipe 28 to the separating tank to enable any heavy residual to pass again through the secondary coil. If desired, fresh oil may be admitted to the secondary 55

coil through pipe 29 controlled by valve 30, and heated water or steam admitted to the inlet of said secondary coil through pipe 31 controlled by valve 33. Also, hydrogen may be admitted to the inlet of the secondary coil through pipe 34 controlled by valve 35.

The condenser 28 discharges through pipe 26x into receiving tank 36, having a side gauge 31. Burner 7 may receive oil from any suitable source which may be blown with air to the burner, as by blower 38 driven by motor 39.

The oil and water are thoroughly mixed by the injector or injectors 4 at the point where the two are brought together. This gives rise to the formation of a spray of oil in an atmosphere of steam if the water has been heated sufficiently, so that it either is steam, or breaks into steam at the time it passes through the injector. In case the water is only hot, but not above 212° F., there results an emulsion of oil and water due to the action of the injector in mixing the two products. This emulsion on reaching the heated coil 3 forms a spray of oil in steam similar to that which would be formed if the water were heated to above 212° F. The resulting spray of oil in an atmosphere of steam passes through the heated coil 3, which coil may be heated to somewhat above 1000° F., and due to the simultaneous action of heat and steam, and also of a catalyst 5 inserted into the latter part of the coil, will, by cracking of the heavy petroleum, produce a small amount of gas, (the amount depending on the temperature used) much motor fuel and some, say 30%, of the original volume of the oil, of a heavy residual oil.

The direction of the flow in the secondary coil is the reverse of that in the primary coil. This is in order that in the lower part of the secondary coil, the pipes which are nearest to the burner 7 will not be overheated. It also has secondary advantages in that, by such treatment, the oil and water vapors which are passing through the coil will be kept as near as possible at the desired temperature for a longer period. The amount of oil passing through the secondary coil may be only one-fourth that passing through the primary coil 3. In other words, its speed through the coil will be less, though still having a high velocity. The coil 6 may carry a catalyst 5x.

The catalysts 5, 5x are inserted in the drawing as if in the last length of the primary and secondary coils. They can be placed in other lengths as well. They can be inserted by removal of the return bends 3x, 6x, on the left of the drawing by unscrewing the flanges indicated.

Any suitable hydrocarbon reactive catalyst may be employed, and in the drawing, the catalysts are shown of metallic mesh and they may comprise surfaces or solid bodies of metallic chromium, nickel, molybdenum oxide, tungsten oxide, and in some cases, other metallic oxides. The tubes themselves may be composed of a high nickel alloy such as chrome-nickel-steel tubes. The chromium and nickel are used as catalysts for the hydrogenation.

The return-bend and flanges indicated on the left side of the kiln can be readily opened up so that in case any one tube becomes injured or needs to be replaced, it may be removed and replaced with a new tube.

In order that heat may not be lost by the return bends which are outside of the kiln proper,

they may be within a casing 9, the doors indicated at 10 in the drawing.

The separating tank 11 is provided to receive, preferably, the product from both the primary and secondary coils, though, if desired, a separate separating tank (not shown) may be used for the products from the secondary coil.

After tank 11 has been in use for a short period of time, it may be so hot due to the evolved steam and vapors of motor fuel, that it may distill over into the condenser products of so high a boiling point that they are useless for motor fuel or kerosene. In such a case, it may be desirable to cool the separating tank, and for this purpose, water sprays are indicated at 12, so that, by turning water upon them, this partial separation into heavy materials to be re-run through the secondary coil and vapor to pass through the condenser to give the desired motor fuel, may be controlled.

In the simultaneous cracking and hydrogenation of the petroleum, hydrogen may, with advantage, be injected along with water vapor and the oil to be cracked and hydrogenated. The steam under these conditions gives some nascent hydrogen, and additional hydrogen has advantages in increasing the speed of hydrogenation.

As hereinbefore stated, hydrogen may be injected from tank 13 along with water and oil, into the secondary coil 6. It can also be injected if desired, into the primary coil at approximately the same point at which the water is injected.

While straight tubes connected by return headers are indicated, there may be substituted, though less desirable, so-called coils made in spiral form. The feed of the materials in these coils may be either concurrent or countercurrent to the supply of heat. My preference is that the materials to be heated be passed out from the primary coil through the hottest point of the coil. As to the secondary coil which handles and recracks the residual oil, my preference is for the materials being heated to pass out from the system through the part of the coil farthest from the burner.

The aggregate length of the coils will be determined by the diameters of the constituent pipes, and by the capacity desired. What is required is a certain time of heating. The higher the speed at which the vapors move through the tubes, the longer the tubes will need to be, or the larger the diameter the tubes will have to be, in order that the material will be given the necessary time while being heated. For example, the primary coil 3 shown in the drawing, may be sixty feet long and made of tubes having an internal diameter of about three inches. The secondary coil 6 may be forty feet in length for the same sized tubes. With such length and diameters of the primary and secondary coils an initial run of East Texas crude will produce a synthetic gas oil rich in low boiling point hydrocarbon. For a commercial standard unit of 1,000 barrel daily capacity, for the primary purpose of producing a high gasoline conversion in the first run and recycled residue from any class of crude charging stock the length of the primary coil may be approximately 600 feet with 3½ inch internal diameter, and the secondary coil may be approximately 500 feet in length with the same internal diameter.

In operation, the temperature employed in the treatment of materials which have not been through a cracking process, as, for example, a low grade crude petroleum, will be about 1200° F., at 75

the lowest, i. e., the hottest part of the primary coil, and will be about 900° F. near the top of the coil. These are temperatures of the coil itself, materials within it will be somewhat cooler.

- 5 For the lower secondary coil which is to handle a material difficult to crack, i. e., the residual oil which has once been through the cracking process, the temperature will be approximately 1200° F. throughout the entire coil. The two ends of 10 the coil will be about the same temperature. My preference is for operation under approximately atmospheric pressure, i. e., that there shall be no closed valves or the like at the discharge points of the coil to give a pressure of more than a few 15 pounds.

The proportion of water to oil will vary from 0.6 to 1.5, depending upon the character of the oil that is cracked. In general, an oil which is hard to crack, i. e., which has been through the cracking process before, will require a larger proportion of water. This water should be raised to 200° F. or more by the pre-heater, and be fed into the coil either as steam or as water ready to burst into steam. Where hydrogen is used, it 20 will be handled in a tank under substantial pressure but will be reduced and injected under a few pounds pressure, above atmospheric pressure. The amount of hydrogen used is small by weight as compared with the weight of the co-mingled oil and water. The volume of hydrogen used will vary with the kind of oil being cracked, but, in general, will be of the order of $\frac{1}{3}$ volume of hydrogen to one volume of steam formed from the water, both being at the same 25 temperature and pressure.

The motor fuel produced by the process is unlike the motor fuel produced by other hydrogenation processes, in that it is largely unsaturated as shown by customary iodine number tests. As 30 produced, it has a yellowish color, but this color can be largely removed by the customary filtration through charcoal or heated clays customarily used in the petroleum industry.

In addition to being unsaturated, the motor fuel contains considerable quantities of ring series hydrocarbons. The motor fuel has the advantage over products produced by other processes of hydrogenation, in that it is a highly anti-knock fuel, and has a high density and consequently, a higher B. t. u. value than the gasolines commonly on the market. In view of the above, it may be used in high compression automobile engines in leaner mixtures than ordinary gasolines, and thereby give, in an automobile motor, greater mileage per gallon than ordinary gasoline.

It is well known in the art that condensable vapor products from the cracking or conversion of petroleum oils under cracking or conversion temperatures may be fixed, as fixed gas, by raising the heat treating temperature, as, for example, by leading the vapors from the cracking apparatus to a superheater or by merely increasing the heat applied to the cracking or conversion apparatus to a substantial degree beyond that required in the production of condensate, and my claims are to be interpreted accordingly in the use of my method for the production of gas.

70 Having described my invention, what I claim and desire to secure by Letters Patent, is as follows:—

1. A process of treating petroleum oil for the conversion thereof into motor fuel, by hydrogenation below the saturation point, which comprises

passing co-mingled petroleum oil and water through a primary conversion zone subjected to a temperature sufficient to vaporize and crack a substantial part of said petroleum oil, the water being in proportion sufficient to retard polymerization of the oil during its said heat treatment, passing the resulting vapor and entrained liquid products to a separating zone wherein liquid is separated from the vapors, leading said liquid from said separating zone directly to a secondary conversion zone subjected to heat higher than that of the primary zone and below that required for conversion of a substantial proportion of said residue into fixed gas, said treatment being under pressure below 20 atmospheres, mixing the resulting products from both conversion zones in said separating zone, removing the lighter vapors of both conversion zones together from the separating zone, and recycling residues from the two conversion zones, with hydrogenous material such as water, through the more highly heated secondary conversion zone.

2. A process of producing motor fuel in accordance with claim 1 in which the passage of the vapors through the primary and secondary zones is substantially at atmospheric pressure.

3. A process of producing motor fuel in accordance with claim 1 in which fresh petroleum oil is passed with the liquid residue into the secondary conversion zone.

4. A process of producing motor fuel in accordance with claim 1 in which fresh water and oil are passed into the secondary zone with the liquid residue.

5. A process of producing motor fuel in accordance with claim 1 in which hydrogen is led into the primary and secondary conversion zones in volume approximately one-third volume of the water vapor in said zones.

6. A process of producing motor fuel in accordance with claim 1 in which the reacting materials are subjected at the discharge end of each zone to the action of a catalyst of the hydrogenation type.

7. The process of producing hydrocarbons of low boiling point by hydrogenation below the point of saturation, which comprises passing co-mingled petroleum oil and water to a primary conversion zone subjected to heat and pressure below 20 atmospheres, passing the resulting vapor and entrained liquid products directly to a separating zone, leading the liquid from said separating zone directly to a secondary conversion zone subjected to higher heat and below that required to convert a substantial proportion of said liquid into fixed gas, leading the products from said secondary conversion zone to said separating zone, removing the light vapors of both conversion zones together from the separating zone and leading the liquid residue from the separating zone back to the secondary conversion zone with hydrogenous material, such as water, and as a step in the process subjecting the heat treated products to the action of a catalyzing agent of the hydrogenation type and to hydrogen passed into the secondary conversion zone.

8. Apparatus for producing hydrocarbons of low boiling point which comprises a heat chamber having a burner at its lower end, a primary conversion coil in said chamber at the upper portion thereof, means for injecting co-mingled oil and water into said primary conversion coil, a separating and expanding chamber of controlled temperature having communication with the outlet end of the primary conversion coil, a second-

ary conversion coil disposed at the lower portion of the heated chamber and exposed to heat of greater intensity and having its outlet at the top, and its inlet at the bottom, so that the outlet sections of the primary and secondary coils lie substantially in the same heat receiving zone within the heated chamber, catalyzing agents disposed within the outlet sections of the conversion coils, a flow connection communicating the base of the separating chamber with the inlet of the secondary conversion coil, means for discharging from the secondary conversion coil into the separating chamber, and means for removing from the separating and expanding chamber the lighter products received from said coils.

9. Apparatus for producing hydrocarbons of low boiling point which comprises a heat chamber, a primary conversion coil in said chamber, 20 at the upper portion thereof, means for injecting co-mingled oil and water into said primary conversion coil, a separating and expanding chamber having communication with the outlet end of the primary conversion coil, a secondary conversion coil disposed at the portion of highest 25 heat of the heated chamber and having its outlet at the top, and its inlet at the bottom, so that the outlet sections of the primary and secondary coils lie substantially in the same heat receiving zone within the heated chamber, a flow 30 connection communicating the base of the separating and expanding chamber with the inlet of the secondary conversion coil, means connecting the top of the separating and expanding chamber with the outlet of the secondary conversion coil whereby the vapors discharged from the latter are mixed in said chamber with the vapors from the primary conversion coil, and means for removing from the separating and expanding 35 chamber the lighter products received from said coils.

10. Apparatus for producing hydrocarbons of low boiling point which comprises a heat chamber, a primary conversion coil in said chamber, 40 at the upper portion thereof, means for injecting co-mingled oil and water into said primary conversion coil, a separating and expanding chamber having communication with the outlet end of the primary conversion coil, a secondary con-

version coil disposed at the portion of the heated chamber receiving the highest heat and having its outlet at the top, and its inlet at the bottom, so that the outlet sections of the primary and secondary coils lie substantially in the same heat receiving zone within the heated chamber, catalyzing agents disposed within the outlet sections of the conversion coils, a flow connection communicating the base of the separating and expanding chamber with the inlet of the secondary conversion coil, vapor discharge means connecting the separating and expanding chamber and the outlet of the secondary conversion coil, means for removing from the separating and expanding chamber the lighter products received from said coil, and means for injecting fresh oil and water within the inlet of the secondary conversion coil with the liquid residue from the separating and expanding chamber.

11. Apparatus for producing hydrocarbons of low boiling point which comprises a heat chamber, a heating means at the base of said chamber, a primary conversion coil in said chamber at the upper portion thereof, means for injecting co-mingled oil and water into said primary conversion coil, a separating and expanding chamber having communication with the outlet end of the primary conversion coil, a secondary conversion coil disposed at the lower portion of the heated chamber and having its outlet at the top, and its inlet at the bottom, so that the outlet sections of the primary and secondary coils lie substantially in the same heat receiving zone within the heated chamber, a flow connection communicating the base of the separating and expanding chamber with the inlet of the secondary conversion coil, means for discharging from the secondary conversion coil into the separating and expanding chamber, means for removing from the separating and expanding chamber the lighter products from said coils, means for injecting fresh oil and water within the inlet of the secondary conversion coil with the heavier products from the separating and expanding chamber, and means for injecting hydrogen into the secondary coil with the liquid residue from the separating and expanding chamber.

RALPH H. MCKEE.
